United States Patent Office.

JOHN H. KEYSER, OF NEW YORK, N. Y.

Letters Patent No. 99,092, dated January 25, 1870.

COAL-STOVE.

The Schedule referred to in these Letters Patent and making part of the same.

To all whom it may concern:

Be it known that I, JOHN H. KEYSER, of the city and county of New York, in the State of New York, have invented a new and useful Improvement in Stoves; and I do hereby declare that the following is a full, clear, and exact description thereof, reference being had to the accompanying drawings, making part of this specification, in which—

Figure 1 is a diametrical section through the upper portion of my improved stove, showing the interior arrangement thereof.

Figure 2 is a diametrical section, taken in a plane at right angles to the sectional plane of fig. 1.

Figure 3 is a perspective view of the bonnet, detached from the stove.

Similar letters of reference indicate corresponding parts in the several figures.

This invention relates to improvements on stoves, which are used for warming rooms, and which are constructed with single cylinders, and direct draught-passages.

The object of my invention is to improve stoves of this class, by the arrangement of a perforated dome or bonnet above the fire-chamber, in such manner that the products of combustion will be arrested, and concentrated over the fire, and then directed forward to the front of the stove on their way to the escape-pipe, thereby effecting a very perfect combustion of the gases, and utilization of fuel, and greatly improving the heating-qualities of the stove, as will be hereinafter explained.

To enable others skilled in the art to understand my invention, I will describe its construction and operation.

In the accompanying drawings, fig. 1, I have represented my invention applied to a single-cylinder surface-burning stove, of which—

A is the body of the stove;

B, an illuminating-section; and

C, a circular, perforated, and adjustable ring, which may be used for admitting air into the combustion-chamber, above the fuel.

D is the top cylindrical section of the stove, from which a pipe, F, leads off to the chimney.

The parts lettered B and C are not claimed under this petition, as they form the subject of claim under a petition for Letters Patent, marked case B, and bearing even date with the filing of this.

The perforated and illuminating-section B has a circular flange, b, applied within its contracted upper end, which flange inclines downward and inward, and forms a deflector for arresting the upward course of some of the products, and turning them downward toward the fire, for more perfect combustion.

This flange or deflector is fully set forth in the Letters Patent granted to me on the 22d day of September, 1868, and is not claimed under this petition.

On this flange a dome or bonnet, E, is supported, which bonnet has an opening, a, through its front side, for the escape of the products into a chamber, c. This bonnet flares downward, and has a rounded top. It receives the heated products within it, and by concentrating and arresting them directly over the incandescent fuel, allows them to be consumed, and thus greatly increases the heating-capacity of the upper section.

The opening a is made through the front of the bonnet E, in order that the products shall be directed toward the front of the stove, and also, to cause the products to take the longest course, on their way from this bonnet to the escape-pipe F.

By reference to figs. 1 and 2, it will be seen that a space, c, is left around and above the bonnet, which space is formed by this bonnet and the top section, and forms a flue for heated products, as above stated. This bonnet E, which may be made of cast-iron, can be so applied as to allow of its removal at pleasure, or it may be permanently secured in place.

The perforated ring C is so located, with reference to the flange b, that air can be introduced into the combustion-chamber, at the upper portion of section B, for applying oxygen to, and thus assisting in the combustion of the gases under the flange b, and in the bonnet E.

Having described my invention,

What I claim as new, and desire to secure by Letters Patent, is—

1. The bonnet E, open in front, and arranged in the top section D, substantially as described.

2. The combination of the bonnet E, with the deflecting-flange b, substantially as described.

JOHN H. KEYSER.
